ACOUSTIC SIGNALING DEVICE

John F. Moran, Jersey City, N. J.

Application February 3, 1932, Serial No. 590,573

10 Claims. (CL 177—7)

My present invention is shown as embodied in a so-called horn of the type commonly employed on automobiles, as warning signals. It relates more particularly to the horns of the type in which the signal waves are generated by an elastic diaphragm which is actuated by fluctuating or intermittent attraction of an electromagnet. The diaphragm is permitted to swing freely on both sides of normal, and the electromagnetic retracting efforts are applied harmoniously with said natural frequency, thereby building up powerful to and fro elastic swing of the diaphragm on both sides of normal.

Heretofore synchronism has been attained, in some cases by employing intermittent fluctuating or alternating currents of predetermined frequency and selecting a diaphragm having a corresponding frequency of free elastic vibration; and in other cases by selecting a diaphragm having a desired frequency of free elastic vibration and then tuning an adjustable circuit controlling element to synchronize the energizing current and resulting electromagnetic attraction to the frequency of that diaphragm.

In certain cases, an interrupter is employed which is independently tuned to the frequency of the diaphragm, in which case, anything varying the natural frequency of the diaphragm or the tune of the interrupter will put the electromagnetic pulls and the diaphragm out of step. In other cases, the diaphragm itself is used as a driving mechanism to actuate the interrupter, but this involves mechanical connection with the diaphragm which interferes with its free swing and to that extent changes its natural frequency and otherwise interferes with its functioning as a free elastic vibrator.

As concerns this aspect of my invention, it contemplates an electromagnet and control mechanism in the horn casing behind the main diaphragm which is practically aperiodic as concerns all frequencies which are desirable for horns of this type. The desirable frequencies are within the range, 350 to 750 complete vibrations per second, and the most desirable range is much narrower than this. Important points are that such aperiodic mechanism is controlled by the diaphragm without preventing its free swing or imposing any appreciable load. This is accomplished by utilizing an elastic medium, specifically the air within the casing, for causing the aperiodic control mechanism to automatically synchronize the current variation with the bodily swings of the diaphragm. Various structurally novel features each involving functional novelty,

may be employed in partial or complete combination, according to the degree of efficiency and perfection of functioning that may be required in any given instance.

In the preferred form, the novel features include contributing factors as follows:

The electromagnet is of course located within the horn casing, in opposite relation to a suitable armature on the rear face of the front diaphragm. Within the casing is a second diaphragm having one face exposed to the air pressures within the casing, so related to or remote from, the main diaphragm that it does not constitute a substantial load tending to limit the amplitudes of swing of the main diaphragm. The opposite face of this supplemental diaphragm is preferably exposed to atmospheric pressure so that internal pressures will be operative to force movements of the supplemental diaphragm. The preferred location of the supplemental diaphragm is in the rear of the electromagnet, preferably coaxial and parallel with the front diaphragm.

An important feature of the supplemental diaphragm is to suppress its natural frequency of free vibration, and this is accomplished first, by limiting its possible movement under air pressure, substantially to and from one side of normal, so that it cannot build up any resonant vibration in its own frequency; second, selecting a diaphragm of high natural frequency as compared with the front diaphragm, so that its elastic return to normal after it has been displaced by internal air pressure will be substantially faster than the varying internal pressures which caused its displacement and its return.

Another important feature of the invention concerns avoiding the effects of resonance in the air column that transmits the pressure changes from the rear face of the sound generating diaphragm to the front face of the sound actuated diaphragm. I have discovered that where the operating electromagnet is located between said diaphragms as in my construction, and where the distance between the diaphragms is substantially less than the quarter wave length of the sound wave produced by the front diaphragm, the air column may be made to actuate the rear diaphragm in proper phase, without utilizing the cumulative effects of air column resonance which have been relied upon in certain prior art devices. For instance, in my device, if the distance between the front and rear diaphragms is $2\frac{1}{2}$ inches (which would be a quarter wave length for 1200 frequency), diaphragms having any of the fundamental frequencies desirable for an

automobile horn, say, 400 to 750 complete bodily swings per second, may be used interchangeably. This proves that the air column functions as a substantially aperiodic medium; and the device 5 does not have to be designed with reference to the frequency of the signal wave produced by the swing of the diaphragm. It will be evident that even in such cases, there will be a substantial time lag between rearward pressure exerted by 10 the front diaphragm and the taking effect of said wave upon the rear diaphragm, but this is desirable because, as explained below, the pressure on the rear diaphragm is utilized to decrease the energizing current in the electromagnet; and it 15 is desirable that this should not be greatly decreased until after the diaphragm has completed its rear swing.

The rear diaphragm having only forced movement rearward from normal and elastic return 20 terminating at normal, is utilized to control the current in the electromagnet, preferably by varying the pressure on the electrode of a microphone in series with the current, although in certain cases, make and break contacts may be substituted 25 for the microphone. The microphone is particularly desirable because sparking is entirely avoided and no deterioration can occur within the microphone; also the microphone is effective for varying the current in the electromagnet in 30 response to mere variations of pressures of the rear diaphragm against the electrodes, even where the decrease of pressure is insufficient to substantially move the center of the diaphragm, thus providing initial weak current variations 35 required to build up the swing of the main diaphragm to the point where the internal pressures will cause positive wide movements of the rear diaphragm, as in full normal operation. The make and break can be employed so as to produce 40 somewhat similar effects by minute arcing between the contacts, with or without complete make and break.

Between the rear diaphragm and the movable element of the microphone or other current varying mechanism, is a link operating as a thrust member normally tensioning the rear diaphragm rearwardly and pressing the movable element of the microphone or other current varying mechanism forwardly; but when pressure on the rear 45 diaphragm forces it rearwardly, the link operates as a tension member to positively retract the movable member of the current varying mechanism. While satisfactory operation may be achieved by rigid coupling, the efficiency of operation 50 may be greatly increased by interposing a lost motion connection, affording predetermined intervals between thrusts and retractions, and during such intervals the air pressures in 55 casing act on the microphone diaphragm to delay releases and reapplications of pressure on the current varying element. The link is preferably adjustable in length so that the initial flexing of the rear diaphragm may be properly determined.

60 The lost motion connection may be either elastic, as where a felt or similar elastic washer is employed; or it may be a complete non-elastic lost motion as by providing a definite degree of longitudinal play within the coupling, as for instance, by having a screw element of the microphone connection formed with threads a predetermined amount smaller than the thread of the diaphragm member of the coupling.

65 The electromagnet is preferably of the iron-clad, central-pole type and its axial length is

preferably as small or smaller than its diameter, thereby minimizing the permissible distance between the front and rear diaphragms without sacrifice of electromagnetic efficiency. In this connection, it is to be noted that the electromagnet may fill up approximately half or more than half the cross-section of the casing, leaving only a relatively narrow air space for front to rear transmission of air waves or pressures from the front diaphragm to the rear diaphragm. It will be further noted that the air space between the rear of the magnet and the rear diaphragm is substantial, so that this, taken with the annulus, constitutes an irregular cup-shape, relatively obstructed cavity, which acoustically considered, is very far from developing any clear resonance such as the casing itself would be if it were empty. This is a factor contributing to aperiodic-response quality of the elastic air medium whereby rearward pressure of the front diaphragm is transmitted to the rear diaphragm. The annular space between the magnet and the casing is obstructed by supports and may be relatively small cross-section so as to have a damping and smoothing effect on air waves transmitted therethrough, but thinness of this space should not be carried to the point of throttling the pressure sufficiently to impose a substantial load on the front diaphragm.

It will be evident that having the rear casing and operative mechanism therein, practically aperiodic as concerns desirable horn frequencies, is of advantage as concerns the front diaphragm. For instance, for a standardized horn, the variation or tolerance permissible for natural frequencies of different diaphragms of the same lot is considerable, thus cheapening manufacture. Furthermore, the same casing and operating mechanism may be standard for horns having diaphragms of widely varying frequencies and constructed so as to give notes of desired degrees of harshness. One feature of the invention is providing a diaphragm having an armature rigidly secured to the diaphragm at its center, but having an overhang sufficient to bring its peripheral edge in contact with the diaphragm when the diaphragm reaches the end of its outward swing. Such an armature may be of relatively great area to bridge the poles of a magnet of great diameter and yet have all but the extreme central portion of the diaphragm free for easy elastic bending.

In this connection, it is to be noted that a diaphragm having such a large armature closely confronting such a large magnet area operates on the air within the casing in an entirely different manner from the operation of the outer surface of that diaphragm, which operates on the atmosphere. On the outside, all of the work goes directly into producing the useful signal wave, whereas in the casing a large part of the work is done by the rear face of the armature which acts somewhat like a push-pull pump pushing out and sucking in air radially between it and the magnet face, and this effect is obviously great when the clearance between the armature face and magnet face is a minimum.

The above and other features of my invention will be more fully understood in connection with the accompanying drawings, in which

Fig. 1 is an axial sectional view of a horn, showing one desirable embodiment of my invention;

Fig. 2 is a greatly enlarged detail view of a

desirable form for the coupling rod shown in Fig. 1;

Fig. 3 is a perspective view of the magnet shell and bracket shown in Fig. 1;

5 Figs. 4 and 5 are detail sectional views showing diaphragm and armature arrangements;

Fig. 6 is like Fig. 1, but showing a modified arrangement of rear diaphragm and microphone; while

10 Figs. 7 and 8 are sectional detail views showing make and break contacts that may be used in place of the microphone in a structure like Fig. 1.

In these drawings, the horn is shown as comprising a cylindrical casing 1, closed practically air-tight at the enlarged forward end by diaphragm 2 and at the rear end by smaller diaphragm 3. The front diaphragm is securely clamped in position by front casing 4 carrying projector 5 through which the sound waves are projected into the air, and the rear diaphragm is secured by rear casing 6, which is in communication with the air through an opening 7. This opening is of such small size and is so located that air waves from the projector have negligible effect in producing pressures on the rear face of diaphragm 3. One advantage of the apparatus is that neither diaphragm is subjected to any violent stress and will operate indefinitely without breakage. Consequently, if desired, the diaphragms may be permanently secured by bending or spinning over the flanges, 4a for the front casing and 6a for the rear casing. The usual diaphragm gaskets 2a, 3a, may be employed to space the diaphragms away from the adjacent metal surfaces, and these gaskets may be metal, paper, cork, or the like, as may be desired. Obviously, screws may be employed in place of flanges for clamping the diaphragm at the front and rear ends of the casing. The rear diaphragm is of much less diameter and may be of greatest thickness in order that its rate of elastic return to normal will be much higher than that of the front diaphragm. The diaphragms are preferably of fine quality spring steel.

45 Within the casing is secured by rivets 8, the anchorage cross-bar 9, carrying the peripheral pole pieces 10, preferably integral therewith, as shown in Fig. 3, and the central pole piece 11. These field pieces are of soft iron and the central pole may be laminated. It is secured by riveting, as shown in Fig. 1.

The energizing coil 12 encircles central pole piece 11, fitting between it and the shell poles 10.

55 The front diaphragm has a relatively massive large-area armature 13, secured to its center as by a rivet 14. As shown in Fig. 1, there are intervening washers as, for instance, a large-area washer 15, between the armature and the rear face of the diaphragm and washers 16, 17 between the diaphragm and the rivet head. It will be understood that a large area washer 15, on the rear of the diaphragm will have the effect of filling a much larger central portion of the diaphragm for the forward swing than will washers 16 and 17, for the rear swing. Consequently, many variations of note quality may be produced by varying the area and thicknesses of these washers. In addition to this, specially harsh effects may be produced by having the washer between the armature and the rear face of the diaphragm, as at 15a, Figs. 4 and 5, thin enough and of small enough area so that at the extreme limit of forward swing of the diaphragm, the peripheral corner of the armature will come in contact

with the bowed diaphragm as shown at 13a, Fig. 5.

The means for varying the current through the magnet coil 12 is shown as a microphone cell comprising a casing 20 and a flexible diaphragm 21, preferably of non-corrosive, non-magnetic metal, such as phosphor-bronze, containing a microphone consisting of electrode 22 fixed to the casing and electrode 23 carried by and movable with the diaphragm 21. These electrodes also 10 may be of phosphor-bronze.

While any desired form of microphonic contact for these electrodes may be employed, I prefer a simple construction consisting merely of registering shallow concavities in the face of 15 electrodes 22 and 23, each containing a carbon ball 24, said balls being of smaller curvature than the cavities but of sufficient diameter to keep the electrodes from contact with each other. The rear electrode has a rigid, preferably integral 20 shank 25 extending through the rear of the casing and insulated therefrom as shown. Shank 25 is preferably utilized to secure the casing in position and at the same time form a circuit connection for the fixed electrode, as by riveting said 25 shank through a plate 26 of insulating material secured to the bridge 9 by screws 27 and formed with a cavity in which the riveted head of 25 is housed, free from contact with the magnet pole piece 11. 30

The front electrode 23 also has a rigid, preferably integral extension 29, whereby it is secured to the diaphragm 21 of the microphone casing as by clamping nut 30. This shank 29 is screw-threaded to form part of an adjustable coupling 35 between the microphone diaphragm 21 and the rear diaphragm 3, the preferred arrangement being that shown on a large scale in Fig. 2. Here the microphone electrode shank 29 is screwed into an internally threaded head 31, which has a 40 shank 32 extending through diaphragm 3 but insulated therefrom by washers 33, 34. The head 31 is clamped in place by nut 35 and jam nut 36.

45 As before explained, the purpose of this screw coupling is to apply suitable pressure on electrode 23 by rearwardly flexing diaphragm 3 the required distance.

The design is such that in operation development of rearward pressure on the rear diaphragm 3 will first operate to relieve the elastic 50 pressure of said diaphragm on said electrode 23 without substantial motion of the center of said diaphragm 3. Thereafter, further rearward movement of diaphragm 3 will positively retract electrode 23. Subsequent decreasing rearward 55 pressure on 3 will cause reverse operation and the pressure on electrode 23 will be accentuated when a vacuum condition tends to suck 3 rearwardly. While the apparatus will operate more or less satisfactorily with the coupling 29, 31, of 60 rigidly fixed length, an important improvement results where there is a lost motion interval between the time of thrust of diaphragm 3 on electrode 23 and the time of retraction by diaphragm 3. As shown in Fig. 2, this lost motion may be 65 provided merely by making the threads of 29 and 39 a loose fit, in the direction of tension and thrust. With such arrangement, the normal thrust condition will bring the threads into bearing as indicated at 40 and, as diaphragm 3 moves 70 to the left and the pressure is released, the diaphragm 3 will continue to move rearwardly for a substantial interval before the other faces 43, of said threads, come into contact so that further retracting movement of diaphragm 3 will 75

take effect as a retracting tension on electrode 23. A lost motion connection of somewhat similar effect, but by elastic development, may be had by making the insulating washers 34 of elastic material. It will be noted that in Fig. 1, the distance between front and rear diaphragm is 2½ inches and as previously explained, this is the quarter wave length for 1200 frequency; hence only a fraction of a quarter wave length for 400 to 750 frequency of swing of the front diaphragm 2. Consequently, the above described satisfactory pressure condition will be established in the horn cavity during the rearward swing of diaphragm 2 and a corresponding vacuum condition will be produced on the forward swing of said diaphragm. An important point is that the pressure phase on 3 will lag substantially behind generation thereof by diaphragm 2, and much further lag in final retraction of electrode 23 will result from the lost motion connection at 40, 43, with the composite result that the times of maximum pull and release by the electromagnet will be in proper phase for efficiently building up wide swings of diaphragm 2. An important contributing factor is that during the lost motion period, when the rear diaphragm 3 is exercising neither pressure nor tension on electrode 23, said electrode will be held firmly pressed forward by the internal pressure which is then taking effect on the rearwardly presented surface of the microphone diaphragm 21. Minus pressure will cause the reverse effect, namely, relief of the microphone pressure during the lost motion part of the elastic return of rear diaphragm 3.

While it is obvious that the 2½ inch distance between diaphragms could be somewhat decreased without changing the structure shown in Fig. 1, there are other designs whereby this distance may be still further decreased, as, for instance, that shown in Fig. 6. In this figure, elements such as casing members 1, 4, 5; diaphragms 2, 3; clamping members 2a, 4a, 3a, 6a; electro-magnet elements, 8, 9, 10, 11, 12; armature 13; etc., may be the same as in Fig. 1, but the distance between diaphragms is greatly reduced, by locating the microphone in the rear of the rear diaphragm; and modifying the structure of the microphone and linkage so that rearward movement of the rear diaphragm will release the pressure on the movable member of the microphone. Some of these differences are as follows:

The microphone, instead of being mounted on the electromagnet bracket 9, is mounted on the back of the rear casing member 6c, which is provided with an insulating plate 26a corresponding to 26 of Fig. 1. The fixed electrode 22a is made in the form of an annulus so that the movable electrode 23a, mounted on diaphragm 21 may be actuated through the bushing 25b, whereby the fixed electrode 22a, and the microphone casing are secured to the rear casing 6c. The link between rear diaphragm 3 is afforded by a screw member 29a fixed to said diaphragm, preferably non-adjustably, as by riveting. This screw member engages an internally threaded screw member 31a which corresponds to 31, Fig. 1, having a screw threaded shank 32a, whereby the screw coupling between 29a and 31a may be adjusted to predetermine the initial tension of rear diaphragm 3. In this case, this screw coupling may have lost motion provision as in Fig. 2, for the same purposes and with the same results.

In Fig. 6, the current enters through binding post a', traverses the coil 12 serially and is led to

29a, when the current flows through 31a to 23a, thence through microphone balls 24 to fixed electrode 22a and out through connection 2, to the other binding post b'. This corresponds to the arrangement shown in Fig. 1, where the current passes from binding post a through the coil and to the shank 25 of the fixed electrode 22, thence through balls 24 to movable electrode 23a, microphone diaphragm 21, microphone casing 20 and out to binding post b'. 10 5

There is a feature of the diaphragm and its armature peculiarly adapting it for the double purpose of efficient operation as a motor and also varying the quality of the note produced. Referring to Figs. 4 and 5, for instance, it will be noted that the front clamping washer 17 is of small diameter as compared with the rear clamping washer 15a. Consequently, at the front end of the forward swing, the clamping washer 15a renders the diaphragm quite stiff and therefore of relatively short and swift elastic movements as compared with the corresponding effect of washer 17 during the rear swing from normal to point of nearest approach to the electromagnet. The point is that the free elastic area of the diaphragm is thus rendered much greater during the part of the swing that is nearest the electromagnet than it is during the part of the swing more remote therefrom. The slow easy movement adjacent the face of the electromagnet permits the latter to act a longer time and more effectively on the armature when it is nearest the magnet poles.

At the same time, the swift short movement of the diaphragm forward of normal generates a higher, shorter time period impulse than does the longer slower swing to the rear side of normal, thereby producing a double note effect although the swing of the diaphragm that creates it is, mechanically considered, a true bodily swing on both sides of normal. I suppose that the comparatively great flexibility and decreased resilience of the diaphragm while in the region of the electromagnet is a substantial factor in causing proper in-phase cooperation of the bodily swings with the air-actuated, microphone control fluctuations of the current in the electromagnet. However, this may be, there is no doubt about the great advantages due to the dissimilar effects of small front clamping washers as compared with the large rear clamping washers. 50

Fig. 7 shows an arrangement wherein make and break contacts 23a, 31a are substituted for the microphone electrodes. In this case, the movable member is rigidly mounted on the rear diaphragm 3, so that there is no lost motion, and there is no equivalent for the microphone diaphragm shown in the other figures. 55

Fig. 8 shows a modified form of make and break, in which there is a lost motion connection between rear diaphragm 3 and the contacts 23b, 31b. The lost motion is provided by having the movable contact carried by spring 50, which is loosely engaged between abutments 51, 52 on a member 53 rigidly but adjustably secured to the center of the rear diaphragm 3. 60 65

In this case, the self closing of the contacts during lost motion intervals is by normal elastic bias of spring 50.

In the foregoing, I have not discussed how the air pressures could be used to actuate the rear diaphragm to produce actuation of the microphone in phase with the diaphragm swings, where the air in the casing cavity corresponds to a quarter, half, three-quarter or full wave length; or 70 75

5 multiples of any of them, for the simple reason that it is uncommercial to make the casing longer or larger than it need to be; particularly where my invention makes phenomenal simplification and efficiency attainable with the short casing. It will be evident, however, that to whatever extent longer casings may be usable, each and all of the other above described combinations, sub-combinations and details of my invention may be use-
10 fully employed.

10 I claim:

15 1. A signaling device, including a tubular member, closed by an acoustic diaphragm of sheet steel rigidly clamped about its periphery and with its outer face exposed to atmosphere and its inner face carrying an armature; and by another elastic diaphragm exposed to and actuated by varying pressures set up within said casing member by operation of the acoustic dia-
20 phragm; and an electromagnet arranged between the diaphragms, in operative relation to said armature; and in combination with all of said parts a microphone cell having another dia-
25 phragm, and a direct mechanical connection through which it is controlled by movements of said rear diaphragm to energize said electromagnet during rearward swing of the acoustic dia-
30 phragm and to release it during its forward swing.

35 2. A signaling device, including a tubular member, closed by an acoustic diaphragm of sheet steel rigidly clamped about its periphery and with its outer face exposed to atmosphere and its inner face carrying an armature; and by another elastic diaphragm exposed to and actuated by varying pressures set up within said casing member by operation of the acoustic diaphragm; and an electromagnet arranged between the dia-
40 phragms, in operative relation to said armature; and in combination with all of said parts a microphone cell having another diaphragm, and a direct mechanical connection through which it is controlled by movements of said rear diaphragm to energize said electromagnet during rearward swing of the acoustic dia-
45 phragm and to release it during its forward swing; said control being through a connection affording independent or lost motion between said rear diaphragm and the microphone diaphragm.

50 3. A signaling device, including a tubular member, closed by an acoustic diaphragm of sheet steel rigidly clamped about its periphery and with its outer face exposed to atmosphere and its inner face carrying an armature; and by another elastic diaphragm exposed to and actuated by varying pressures set up within said casing member by operation of the acoustic diaphragm; and an electromagnet arranged between the dia-
55 phragms, in operative relation to said armature; and in combination with all of said parts a microphone cell having another diaphragm, and a direct mechanical connection through which it is controlled by movements of said rear dia-
60 phragm to energize said electromagnet during rearward swing of the acoustic diaphragm and to release it during its forward swing, said control being through a connection affording lost motion between said rear diaphragm and the microphone during a portion of the rearward and forward movements of said rear diaphragm.

65 4. A signaling device, including a tubular member, closed by an acoustic diaphragm of sheet steel rigidly clamped about its periphery and with its outer face exposed to atmosphere and its inner face carrying an armature; and by another elastic diaphragm having one face only exposed to the varying pressures set up in said casing by said main diaphragm, a circuit con-
70

75 elastic diaphragm exposed to and actuated by varying pressures set up within said casing member by operation of the acoustic diaphragm; and an electromagnet arranged between the dia-
80 phragms, in operative relation to said armature; and in combination with all of said parts a microphone cell having another diaphragm, and a direct mechanical connection through which it is controlled by movements of said rear diaphragm to energize said electromagnet during rearward swing of the acoustic dia-
85 phragm and to release it during its forward swing, said control being through a connection affording lost motion between said rear diaphragm and the microphone during an early portion of the rearward movement and a late portion of the forward movement of said rear diaphragm.

90 5. A signaling device, including in combination a tubular member, closed by an acoustic dia-
95 phragm of sheet steel rigidly clamped about its periphery and with its outer face exposed to atmosphere and its inner face carrying an armature; and by another elastic diaphragm actuated by and in accordance with varying pressures set up within said casing member by operation of the acoustic dia-
100 phragm; and an electromagnet arranged between the diaphragms, in operative relation to said armature; the distance between said diaphragms being less than a quarter length of a sound wave corresponding to the period of free elastic vibration of said acoustic diaphragm, in combination with a microphone controlled by movements of said rear diaphragm to energize said electromagnet during rearward swing of the acoustic dia-
105 phragm and to de-energize it during its forward swing.

110 6. A signaling device, including in combination a tubular member, closed by an acoustic dia-
115 phragm of sheet steel rigidly clamped about its periphery and with its outer face exposed to atmosphere and its inner face carrying an armature; and by another elastic diaphragm exposed to and actuated by varying pressures set up within said casing member by operation of the acoustic dia-
120 phragm; and an electromagnet arranged between the diaphragms, in operative relation to said armature; the distance between said dia-
125 phragms being less than a quarter length of a sound wave corresponding to the period of free elastic vibration of said acoustic diaphragm, in combination with a microphone controlled by movements of said rear diaphragm to energize said electromagnet during rearward swing of the acoustic dia-
130 phragm and to release it during its forward swing, said control being through a connection affording independent or lost motion between said rear diaphragm and the microphone.

135 7. A signaling device including a casing, an elastic main diaphragm of sheet steel rigidly clamped about its periphery and having its front face exposed to atmosphere and its rear face closed in by a casing, a movable member of elec-
140 tronagnetic material, secured to the rear face of the main diaphragm and an electromagnet adapted to attract said movable member to re-
145 tract said diaphragm and then release the same, said electromagnet being rigidly mounted in spaced relation to the walls of the casing so as to afford free peripheral space enclosing an air column for propagation of waves from the rear face of the main diaphragm to the rear of said casing, and in combination with all of said parts another elastic diaphragm having one face only exposed to the varying pressures set up in said casing by said main diaphragm, a circuit con-
150

- troller for variably energizing said electromagnet, and connecting means between the latter diaphragm and the circuit controller, for actuating the controller to energize the magnet in step with the bodily swings of the main diaphragm.
8. A signaling device including an elastic main diaphragm of sheet steel rigidly clamped about its periphery and having its front face exposed to atmosphere and its rear face closed in by a casing, a movable member of electromagnetic material, secured to the rear face of the main diaphragm and an electromagnet adapted to attract said movable member to retract said diaphragm and then release the same, and in combination with all of said parts another elastic diaphragm having one face only exposed to the varying pressures set up in said casing by said main diaphragm, a circuit controller for variably energizing said electromagnet, and lost motion connecting means between the latter diaphragm and the circuit controller, for actuating the controller to energize the magnet in step with the bodily swings of the main diaphragm.
9. A signaling device including a main diaphragm of spring metal, an armature carried by said diaphragm, a casing member and means for rigidly clamping the diaphragm about its periphery to form a closed front end for said casing, an electromagnet supported in the casing for intermittently attracting said armature and actuating said diaphragm and, in combination with all said parts, means for intermittently energizing said electromagnet in step with the natural elastic swing of said diaphragm as determined by elasticity and inertia of said diaphragm and armature; said means including a secondary dia-

phragm in the rear of the electromagnet with its face exposed to and actuated by changes of pressure within the casing due to the bodily swings of said main diaphragm, means for limiting vibratory movements of said secondary diaphragm so as to prevent resonant vibration thereof, a microphone for controlling flow of current through the electromagnet and means for transmitting motion of said secondary diaphragm to said microphone.

10. A signaling device including a main diaphragm of spring metal, an armature carried by said diaphragm, a casing member and means for rigidly clamping the diaphragm about its periphery to form a closed front end for said casing, an electromagnet supported in the casing for intermittently attracting said armature and non-positively actuating said diaphragm and, in combination with all said parts, means for intermittently energizing said electromagnet in step with the natural elastic swing of said diaphragm as determined by elasticity and inertia of said diaphragm and armature; said means including a secondary diaphragm in the rear of the electromagnet with its face exposed to and actuated by changes of pressure within the casing due to the bodily swings of said main diaphragm, means for limiting vibratory movements of said secondary diaphragm so as to prevent resonant vibration thereof, a microphone for controlling flow of current through the electromagnet, and a lost motion linkage through which the movements of the secondary diaphragm, are applied to vary the resistance of the microphone.

JOHN F. MORAN.
